UNITED STATES PATENT OFFICE.

DAVID ALLEN, OF SAN FRANCISCO, CALIFORNIA.

COLLAR SUPPORT AND NECKTIE HOLDER.

Application filed March 18, 1925. Serial No. 16,355.

To all whom it may concern:

Be it known that DAVID ALLEN, a citizen of the United States, residing at San Francisco, in the county of San Francisco and State of California, has invented certain new and useful Improvements in Collar Supports and Necktie Holders, of which the following is a specification.

My invention is a collar stiffener support and necktie holder, adapted to be placed around a turn-over collar between the neck band and the fold over part. The invention comprises a metallic band or strip which may be placed around a collar and forms a stiffener for soft collars holding them better in shape, and at the same time forms a necktie holder. The necktie is fastened on to the support by looping over and fastening into a knot, and does not itself pass around the collar and the neck of the wearer.

My invention may be more specifically defined as a metal strip having a sleeve secured to one end through which the other end, after passing around the neck band of a collar, and underneath the folded part of the collar, is adapted to be bent over the sleeve and thereby secures the strip in place. The folded part of the strip may be slid around the collar or a necktie may be tied on the support after looping over the bent or folded portion of the metal strip. My invention is particularly adapted for actual use by wearers, but in addition forms an excellent means for displaying collars and neckties in a haberdashery. In this latter use, my device is particularly adapted to hold soft collars in shape and neckties fastened in a manner similar to that in ordinary use, no matter whether these be of the four-in-hand type or bow ties. My invention will be more clearly understood from the following description and drawings, in which:

Figure 1 is an elevation of the band forming the collar support and necktie holder in disconnected position.

Figure 2 is a plan of the band or strip, threaded through the fixed sleeve on one end and bent over to lock it in place.

Figure 3 is a view of collar supporting band, and necktie holder in position around a collar between the neck band and the fold over part of the collar. This shows the device as it would be used by a wearer or to display collars and neckties.

In the drawings, the band 1 is formed with a squared end 2 having a sleeve 3

formed of a narrow strip of metal bent over and secured by a rivet 4 or the like, to the band 1. The opposite end of the strip is preferably formed with a pointed end 5, in order that it may be threaded through the slot 6 formed by the sleeve. When the strip has the end 5 threaded through the sleeve, the end is bent over or folded back as indicated at 7, Figure 2. In this manner the band is secured from unfastening.

The band is preferably made of a soft metal, which will bend readily and may be flattened out again, such as a soft iron plated, brass, suitably plated, tin or the like. I have found that with the proper metal the device may be used a great many times without breaking at the fold of the strip. There is a certain amount of springiness of the folded end 7 as shown in Figure 2, which holds a necktie more securely in position.

As shown in Figure 3, the band 1 is inserted in a collar 8 between the neck band 9 and the folded over part 10, and clamped in front as shown by dotted lines, by bending the end 7 over as shown in Figure 2. A necktie 11 is tied over the band, hiding the sleeve 3 and the folded or bent part 7. The tie is very simply secured to this by merely forming a loop and then a slip knot with the tie. Bow ties, stocks, or other kind of ties may be used if desired.

It will be readily seen that the band will hold the collar in adjusted position and especially with soft collars, will hold them in shape and more or less prevent creasing. As the neckties do not have to be drawn around the collar they do not make a bulky appearance or pull on a person's neck, moreover, the ties are not destroyed by pulling them through very flattened collars.

With my collar stiffener support and necktie holder, collars may be worn in which the neck band and folded over part are pressed and laundered very tight together. With this type of collar it is very difficult to secure the four-in-hand type of necktie. It will be apparent that my invention can be considerably modified to suit special types of collars or different modes or fads in neckties.

Having described my invention, what I claim is:—

1. A collar stiffener and tie holder comprising a pliable metal strip adapted to extend around a collar between the neck band and the folded over portion thereof, said

strip being pointed at one end and having a sleeve arranged upon its other end, said pointed end being adapted to be passed through said sleeve and bent back upon itself
5 to fasten the strip in position upon the collar.

2. A collar stiffener and tie holder comprising a pliable metal strip adapted to extend around a collar between the neck band
10 and the folded over portion thereof, said

strip having one end pointed and the other end blunt, a sleeve secured upon said blunt end, said pointed end being adapted to be passed through said sleeve and bent back upon itself, whereby the strip is fastened in position and a portion for attaching a neck tie is provided.

In testimony whereof I affix my signature.

DAVID ALLEN.
